UNITED STATES PATENT OFFICE.

EDWARD A. JOHNSTON, OF CHICAGO, ILLINOIS, ASSIGNOR TO INTERNATIONAL HARVESTER COMPANY, OF CHICAGO, ILLINOIS, A CORPORATION OF NEW JERSEY.

AUTOMATIC HORSE-RAKE.

SPECIFICATION forming part of Letters Patent No. 781,656, dated February 7, 1905.

Application filed December 21, 1903. Serial No. 185,945.

To all whom it may concern:

Be it known that I, EDWARD A. JOHNSTON, a citizen of the United States, and a resident of Chicago, in the county of Cook and State 5 of Illinois, have invented certain new and useful Improvements in Automatic Horse-Rakes, of which the following is a specification sufficiently clear and exact to enable those skilled in the art to which it appertains to make and 10 to use the same.

The invention relates to horse-rakes, and more especially to that class known as "draft-dumpers," and has for its object to provide means whereby the initial movement of the 15 rake-teeth in the dumping operation, which movement is due to the resistance of the load, once permitted to act is instrumental in effecting a connection between the tooth-supporting frame and one or more traction-wheels 20 to dump the load, to provide manual means for making said connection which shall operate independently of said initial movement, to provide manual means for giving the teeth 25 said initial movement for the purpose above stated, to provide means for positively maintaining said connection until the dumping operation is completed, to provide means whereby the advance of the rake is effective in disconnecting the tooth-supporting frame from 30 the wheel or wheels, and to provide a tooth-supporting frame and means carried thereby for securing the teeth in position, whereby the 35 space between them may be adjusted.

Other improvements in the details of construction will be pointed out as the description proceeds.

An embodiment of the invention is shown in the accompanying drawings, forming a part 40 of this specification, in which like characters of reference designate like parts.

Referring to the drawings, Figure 1 is a fragmentary plan view of the machine, showing the parts in the position they assume when the teeth are in their normal or working 45 position. Fig. 2 is a sectional side elevation taken on a plane indicated by the line 2 2 of Fig. 1, showing the parts in a position corresponding to that shown in Fig. 1, the

tooth nearest said plane being removed. Fig. 3 is a sectional side elevation taken on a 50 plane indicated by line 3 3 of Fig. 1, showing the parts in a position corresponding to that shown in Fig. 1. Fig. 4 is a sectional side elevation corresponding to Fig. 3, showing the parts in the position they assume when 55 the teeth are in their elevated or dumped position. Fig. 5 is a sectional side elevation of the tripping mechanism, taken on a plane indicated by line 2 2 of Fig. 1, showing its 60 details of construction and the position it assumes when the teeth are in their normal or working position. Fig. 6 is a sectional side elevation corresponding to Fig. 5, showing the tripping mechanism in the position it assumes when the teeth are in their elevated or 65 dumped position. Fig. 7 is a plan view, partly in section, of a portion of the parts shown in Fig. 6. Fig. 8 is a perspective view of a portion of the parts shown in Fig. 5, showing them in a corresponding position. 70 Fig. 9 is a fragmentary plan view of the tooth-supporting frame, showing a plurality of tooth holders or sockets and their relative position when the teeth are to be closest together. Fig. 10 is a plan view corresponding 75 to a portion of Fig. 9, showing a plurality of tooth holders or sockets and their relative position when the teeth are to be farthest apart. Fig. 11 is a sectional side elevation taken on a plane indicated by line 11 11 of Fig. 9, 80 showing the relation between the tooth, the tooth holder or socket, and the tooth-supporting frame and the means for securing the teeth in position. Fig. 12 is a side elevation of a tooth holder or socket.

Referring more especially to Fig. 1, it will be seen that the rake is provided with a tooth-supporting frame (designated by A) which has two transverse members—one the rod *a*, which carries the tooth holders or sockets *B'*, 90 into which the bent ends of the teeth *B* are secured, as will be described later, and the other the shaft *a'*, which in this instance is a pipe upon which the teeth are supported. This shaft, having extensions *c*, provides a 95 convenient axle for the supporting and trac-

tion wheels C, which are held in position thereon by any suitable means. The rod a and the shaft a' are connected by means of brackets a^2 , one at each end, the bracket a^3 at the center, and 5 the brackets a^4 , one between each of the first-named brackets. Any desired number of brackets corresponding to a^4 may be provided which will be determined by the length of the rake. Pivotally connected to this frame is 10 the draft-frame D, which consists of a medial longitudinal member d and the side members d' , located equidistant on each side thereof, and a transverse member d^2 , all of which are united by suitable securing means. The member d is provided with the bearing d^3 and the members d' with the bearings d^4 , within which 15 the shaft a' of the tooth-supporting frame turns when the teeth are raised to their elevated or dumped position or lowered to their 20 normal or working position, as will soon be described. When the rake is intended to be drawn by one horse, as herein shown, the side members d' are preferably extended beyond the transverse member d^2 and made to converge, 25 thereby providing convenient means for securing the thills d^5 . The K-brace d^6 provides the necessary rigidity to the thills and the frame as a whole. The whiffletree d^7 is connected to the medial member in the usual 30 manner. Upon this member also is mounted, by means of a suitable bracket, the seat-spring D', which carries the usual seat (not shown) for the driver.

By turning the tooth-supporting frame A 35 in the bearings d^3 and d^4 of the draft-frame it will be seen that the teeth B may be raised from their working position to their dumped position, or vice versa, as shown in Figs. 3 and 4. In order to maintain them positively, 40 in either position or in any intermediate one, it is necessary to provide holding means connected to the tooth-supporting frame and to some relatively stationary part. The holding means herein shown consist of the post E, secured to the shaft a' , the bell-crank foot-lever E', pivotally connected to the draft-frame within easy reach of the foot of the driver, and the link e , connected to each, as shown in 45 Figs. 3 and 4. These parts are so proportioned 50 that their pivotal points are almost in line when the teeth are in their working position, whereby the driver is enabled easily to hold the latter down to their work. A stop is provided to prevent the pivotal points of the holding means from coming into line, which would form a dead-center and prevent the proper operation of the machine, as will be pointed out later. This stop consists of the block e' , secured to the extension e^2 of the link e , which 55 is adapted to engage the holding foot-lever E'. By referring to Fig. 4 it will be seen that the parts which form the holding means for the tooth-supporting frame are so proportioned also that the pivotal points are nearly 60 in line again when the teeth are raised to their 65

dumped position, whereby they may be held in that position by a slight pressure in a reverse direction on the foot-lever. Secured to the post E is the hand-lever E'', which is also within easy reach of the driver, whereby the 70 teeth may be raised to the dumped position at will. The counterbalancing-spring e^3 , which reacts between the foot-lever E' and the post E, is provided to facilitate the raising of the teeth to the dumped position. Secured 75 to the link e at some convenient point is the hook e^4 , which is adapted to engage the foot-lever E' to hold the teeth in their dumped position to facilitate transportation over roads or elsewhere. Since some drivers prefer to 80 walk behind the rake instead of riding on it, the hand-lever E'' is provided to meet this requirement. It is preferably integral with one member of the link e . By this means the teeth may as readily be held in their working 85 position as by the foot-lever just described and the operation of the rake controlled, as will be explained later.

Even though the weight of the teeth is counterbalanced, as above described, the labor of continually raising them to dump the load becomes arduous. Hence it is desirable to take this work off of the driver and place it upon the draft-animal. This is readily accomplished by providing means for throwing 95 the tooth-supporting frame into connection with the supporting-wheels, whereby it and the teeth carried thereby are given a partial revolution until it is disconnected. The means herein shown consist of the usual pawl-shaft 100 F, journaled in the tooth-supporting frame A, which shaft is provided at the outer ends with pawls f . These pawls are adapted to engage ratchets c' , formed integral with the hubs of the traction-wheels C, thereby forming 105 a clutch for each wheel. The bearings for the outer ends of the pawl-shaft and the housings for the pawls and the ratchets are made integral with the brackets a^2 , as shown in Fig. 1. For convenience in manufacture 110 this pawl-shaft is preferably made in two parts and connected together at the center by suitable means. As herein shown this means consists of the clamp f' , which is integral with the trip-operating arm f^2 . The link f^3 connects 115 this arm with the trip foot-lever F', which is suitably mounted in the seat-supporting bracket above described and is in convenient reach of the driver's foot. By this means the pawl-shaft may be rocked and the pawls 120 at the ends thereof be thrown into engagement with the ratchets of the traction-wheels, respectively, and the teeth raised to the dumped position as the rake is advanced by the draft-animal. The pivotal connection between 125 the tooth-supporting frame and the draft-frame being just short of a dead-center permits the operation, since the driver at this time releases his foot from the holding-lever. It is a known fact that the resistance which 130

the hay or other crop offered in being dragged over the ground when a sufficient quantity has been collected to form a windrow produces a movement about the axis upon which the teeth revolve, which, if permitted to act, would revolve the teeth a partial revolution, but not a sufficient amount to clear the windrow. To make the rake automatic in its operation, means is herein provided whereby this initial movement of the rake-teeth in the dumping operation is utilized to throw the pawls into engagement with the ratchets of the traction-wheels to dump the load. This means consists of the trip-arm G, secured to the pawl-shaft F and preferably integral with the trip-operating arm f² above mentioned. The arm G is provided with a projection, herein shown in the form of the antifriction-roller g, which is adapted to engage the inclined surface g' of a relatively stationary cam G'. This cam is preferably formed integral with the bracket d³ of the draft-frame. When the teeth are in their working position, the antifriction-roller g lies immediately behind the cam G', as shown in Fig. 5. On the opposite side of the trip-arm G and preferably integral with the bracket d³ is the post d⁵, which has an arch-shaped top adapted to carry the trunnions of the collar g². In this collar is slidably mounted the eyebolt g³, which is provided with the spring g⁴, adapted to react between the collar g² and suitable retaining means secured to the end of the bolt. The eye of this bolt is pivotally connected with the trip-arm in such a manner that the tendency of the spring is to hold the arm always in its normal position regardless of the direction of deflection of the arm—i. e., its tendency is to hold the center of the eye of the bolt in line with the centers of the trunnion and the pawl-shaft. The cam G' is also provided with the delay-surface g⁵, against which the antifriction-roller bears during the dumping operation, as will soon be pointed out.

During the initial movement of the rake-teeth the antifriction-roller g moves down the inclined surface g' against the action of the spring g⁴ and along the delay-surface g⁵, thereby throwing the pawls into engagement with the ratchets of the wheels and holding them positively against premature disengagement, thus insuring the completion of the dumping operation. When the teeth have been raised to their dumped position, the antifriction-roller engages the rib g⁶, whereby the pawls are disengaged from the ratchets of the wheels and the trip-arm G is returned to its normal position relative to the tooth-supporting frame by the spring g⁴, as shown in Fig. 6. The teeth then gravitate to their working position, and the antifriction-roller of the trip-arm moves over the top of the cam G', is raised thereby against the action of the spring g⁴, and is dropped into its normal position behind the inclined surface g'.

The above operation may be effected at any other time than when a sufficient amount of hay has been collected to produce the initial movement above referred to by operating the trip foot-lever F', as shown by dotted lines in Fig. 5, or the requisite amount of initial movement may be given by means of either the hand-lever E² or the hand-lever E³. When it is desired to dump the rake while it is standing still, it may be done by means of a hand-lever E², as above suggested. The antifriction-roller of course would pass under the cam in the usual manner and throw the pawls into engagement with the ratchets of the wheels, which would click harmlessly over the ratchets as the tooth-supporting frame which carries them is turned, the shaft having sufficient resilience to permit it. Many means have heretofore been devised for effecting a connection between the tooth-supporting frame and the traction-wheels; but the means herein shown is automatic in its action and much simpler and more effective than any prior ones.

Rigidly secured to the draft-frame D is the cleaner-frame H, which consists of a plurality of bars reaching rearward of the axle between the teeth for the purpose of stripping or cleaning the hay therefrom when the rake is dumped. The outer bars h are preferably integral with a transverse bar h', to which the remaining bars are secured. Three of these bars are preferably formed by prolonging the bars d and d'. The outer bars h' are provided with bearings h², similar to bearings d³ and d⁴, within which the axle turns. As many additional cleaner-bars, as h³, may be provided as the length of the rake requires. These bars are bent up at their rear ends in the form of a loop h⁴, and the bars d, d', and h are provided with looped members h⁵, the object of which is to prevent the teeth from being deflected and caught over the bars, which would prevent their return to working position. To prevent the teeth from being raised too high, which would carry their center of gravity beyond their support and prevent their return to working position, the bearings d³, d⁴, and h² are provided with stops e⁵, with which certain teeth contact.

It is often desirable to vary the spacing of the teeth to suit the varying conditions and kinds of crops raised. A very efficient means of accomplishing this end is shown in Figs. 9, 10, and 11. The tooth holders or sockets B' are provided with bosses b on each side, through holes in which the supporting-rod a passes. On each side of the sockets at the side of the bosses are the projections b', which extend a predetermined distance beyond the end of the bosses, the object of which will soon be made evident. When the sockets are arranged so that the projections b' of the adjacent sockets come on opposite sides of the rod a, the bosses b will abut and the teeth be

arranged in their closest position. When it is desired to arrange the teeth farther apart, it is only necessary to turn each alternate socket around so that the projections b' abut 5 instead of the bosses, as shown in Fig. 10. It will be seen that these sockets might readily be designed so that each alternate one could be turned about its longitudinal axis in order to make either the bosses or the projections 10 abut at will for the above purpose instead of turning them laterally. Either or both of the bosses of each socket might be made adjustable relative to the socket and be provided with a plurality of projections adapted to abut 15 with the adjacent socket or corresponding projections thereon for the above purpose. Hence I do not wish to be limited to the exact construction herein shown. Between the supporting-rod and the end of the socket the bent 20 end b^2 of the tooth B is inserted and held in place by a cotter b^3 , which passes through the socket above the tooth. A corresponding space is provided between the rod and the opposite end of the socket for the purpose of receiving the tooth when the socket is turned 25 around.

It is thought that the operation of the rake will be understood from the above description of its construction and the function of 30 its several parts; but, briefly reviewed, it is substantially as follows: As the rake is drawn through the field the teeth are held in their working position by the driver by means of the foot-lever E' or, in case he is walking behind the rake, by means of the hand-lever E³. When sufficient hay or other crop has been 35 collected to form a windrow, the driver releases the foot-lever or the hand-lever just referred to, as the case may be, and the initial 40 movement in the dumping operation imparted to the tooth-supporting frame by the resistance offered by the accumulated hay is effective in automatically throwing the pawls into engagement with the ratchets of the 45 wheels. When once the pawls are thrown into engagement with the ratchets, they are held positively there until the dumping operation is completed. As soon as the load has 50 been dumped the pawls are automatically disengaged from the ratchets and the teeth permitted to gravitate to their working position, when the operation is repeated. When it is 55 desired to dump the rake at any other time than when a sufficient load has been collected to produce the necessary initial movement of the tooth-supporting frame, this movement may be imparted manually by means of either hand-lever, or the pawl-shaft may be operated by means of the trip foot-lever. As above 60 described, the rake may be dumped while standing still by means of the hand-lever E² when so desired.

Having thus described my invention, what I claim as new, and desire to secure by Letters 65 Patent, is—

1. In a wheeled rake, the combination of supporting-wheels, tooth-carrying means, clutching means between said means and one or more of said wheels, a relatively stationary member, and means which traverses said member and is positively operated thereby to throw said clutching means into engagement. 70

2. In a wheeled rake, the combination of supporting-wheels, a tooth-carrying frame, and means whereby the resistance of the load 75 is instrumental in effecting a connection between said frame and one or more of said wheels, said means comprising a relatively stationary member and a movable member which traverses said member and is positively operated thereby. 80

3. In a wheeled rake, the combination of supporting-wheels, tooth-carrying means, clutching means between said means and one or more of said wheels, relatively stationary 85 members, and means which traverses said members and is positively operated thereby to throw said clutching means into and out of engagement, respectively. 90

4. In a wheeled rake, the combination of supporting-wheels, a tooth-carrying frame, means whereby the resistance of the load is instrumental in effecting a connection between said frame and one or more of said wheels, said means comprising a relatively stationary 95 member and a movable member which traverses said member and is positively operated thereby, and means also for operating said movable member to disconnect said frame. 100

5. In a wheeled rake, the combination of supporting-wheels, tooth-carrying means, clutching means between said means and one or more of said wheels, a relatively stationary member, and means which traverses said member and is positively operated thereby to 105 throw said clutching means into and to hold the same in engagement. 110

6. In a wheeled rake, the combination of supporting-wheels, a tooth-carrying frame, and means whereby the resistance of the load 110 is instrumental in effecting a connection between said frame and one or more of said wheels and whereby said connection is positively maintained during the dumping operation, said means comprising a relatively stationary member and a movable member which contacts therewith. 115

7. In a wheeled rake, the combination with the traction-wheels, of a tooth-supporting frame, holding means therefor, and tripping means whereby, when said holding means is released, the resistance of the load is instrumental in effecting a connection between said frame and traction-wheels, said tripping means comprising a relatively stationary member and a movable member which traverses said stationary member and is positively operated thereby. 120

8. In a wheeled rake, the combination with the traction-wheels, of a tooth-supporting 125

frame, holding means therefor, tripping means whereby, when said holding means is released, the resistance of the load is instrumental in effecting a connection between said frame and traction-wheels, said tripping means comprising a relatively stationary member and a movable member which traverses said stationary member and is positively operated thereby, and means also for operating said movable member to disconnect said frame from said traction-wheels.

9. In a wheeled rake, the combination of a traction-wheel, a tooth-supporting frame, a clutch, a clutch-operating shaft, a trip-arm secured thereto, and a relatively stationary member which said trip-arm traverses.

10. In a wheeled rake, the combination of a traction-wheel, a tooth-supporting frame, a pawl carried by said frame, and means whereby the resistance of the load is instrumental in operating said pawl to effect a connection between said frame and traction-wheel, said means comprising a shaft for operating said pawl, a trip-arm secured to said shaft, and a relatively stationary cam with which said trip-arm contacts.

11. In a wheeled rake, the combination with the traction-wheels having ratchets secured thereto, of a tooth-supporting frame, a holding-lever therefor, pawls carried by said frame, and means whereby, when said holding-lever is released, the resistance of the load is instrumental in operating said pawls to throw them into engagement with the ratchets of said traction-wheels, said means comprising a shaft for operating said pawls, a trip-arm secured to said shaft, and a relatively stationary cam with which said trip-arm contacts.

12. In a wheeled rake, the combination with a traction-wheel, of a tooth-supporting frame, a holding-lever therefor, a pawl-shaft, and means whereby, when said holding-lever is released, the resistance of the load is instrumental in operating said pawl-shaft to effect a connection between said frame and traction-wheel and whereby said connection is positively maintained during the dumping operation, said means comprising a trip-arm secured to said pawl-shaft and relatively stationary cam and delay surfaces with which said trip-arm contacts.

13. In a wheeled rake, the combination with the traction-wheels, of a tooth-supporting frame, a holding-lever therefor, a pawl-shaft, means whereby, when said holding-lever is released, the resistance of the load is instrumental in operating said pawl-shaft to effect a connection between said frame and traction-wheels, said means comprising a trip-arm secured to said pawl-shaft and a relatively stationary cam-surface with which said trip-arm contacts, a corresponding delay-surface for positively maintaining said connection during the dumping operation, and a second cam-surface

face with which said trip-arm contacts, whereby the advance of the rake is effective in operating said pawl-shaft in a reverse direction to disconnect said frame from said traction-wheels.

14. In a wheeled rake, the combination with the traction-wheels, of a tooth-supporting frame, a holding-lever therefor, a pawl-shaft, and means whereby, when said holding-lever is released, the resistance of the load is instrumental in operating said pawl-shaft to effect a connection between said frame and traction-wheels and whereby said connection is positively maintained during the dumping operation and whereby the advance of the rake is effective in operating said pawl-shaft in a reverse direction to disconnect said frame from said traction-wheels, said means comprising a trip-arm secured to said pawl-shaft and a relatively stationary member having suitable cam and delay surfaces.

15. In a wheeled rake, the combination of a traction-wheel, a tooth-supporting frame, means whereby the resistance of the load is instrumental in effecting a connection between said frame and wheel, said means comprising a relatively stationary member and a movable member which contacts therewith, and manual means also for operating said movable member to effect said connection.

16. In a wheeled rake, the combination with the traction-wheels, of a tooth-supporting frame, holding means therefor, tripping means whereby, when said holding means is released, the resistance of the load is instrumental in effecting a connection between said frame and traction-wheels, said means comprising a relatively stationary member and a movable member which contacts therewith, and manual means also for operating said movable member to effect said connection.

17. In a wheeled rake, the combination with the traction-wheels, of a tooth-supporting frame, a holding-lever therefor, a pawl-shaft, means whereby, when said holding-lever is released, the resistance of the load is instrumental in operating said pawl-shaft to effect a connection between said frame and traction-wheels, said means comprising a trip-arm secured to said pawl-shaft and a relatively stationary cam-surface with which said trip-arm contacts, a corresponding delay-surface for positively maintaining said connection during the dumping operation, and a foot-lever connected with said trip-arm for effecting said connection.

18. In a wheeled rake, the combination with the traction-wheels, of a tooth-supporting frame, a relatively stationary draft-frame pivotally connected therewith, a link pivotally connected with said tooth-supporting frame at a point outside its axis of revolution, a holding foot-lever pivotally connected with said link and also with said draft-frame, a stop for preventing a dead-center between said link

and holding foot-lever, a dumping hand-lever secured to said frame, a supplemental combined dumping and holding hand-lever integral with said link, and a counterbalancing-spring which reacts between said foot-lever and said tooth-supporting frame.

19. In a wheeled rake, a tooth-supporting frame having tooth holders or sockets provided with abutting means for varying the space between adjacent teeth when the abutting means of each alternate socket is moved.

20. In a wheeled rake, a tooth-supporting frame having tooth holders or sockets provided with projections which abut for the purpose of adjusting the space between the teeth when the adjacent sockets are turned relatively, and means for holding the sockets in operative position.

21. In a wheeled rake, the combination with the teeth, of a tooth-supporting frame, and tooth holders or sockets carried thereby provided with abutting means for adjusting the space between the teeth when the abutting means of the adjacent socket is moved.

25 22. In a wheeled rake, in combination with

the teeth and the tooth - supporting frame, tooth holders or sockets provided with a plurality of projections at the sides thereof which projections abut with the adjacent socket when in position for the purpose of varying the space between the teeth when the adjacent sockets are turned relatively, and means for detachably securing the teeth thereto.

23. In a wheeled rake, in combination with the teeth and the tooth - supporting frame, tooth holders or sockets each having a plurality of projections of different lengths on each side, said projections abutting with corresponding projections on the adjacent holders or sockets when in position, whereby, when the adjacent sockets are turned relatively, the space between the teeth is adjusted, and means for holding the sockets in operative position.

In testimony whereof I have signed my name to this specification in the presence of two subscribing witnesses.
